COLLAPSIBLE TIRE BUILDING FORM

Henry C. Bostwick, Akron, Ohio, assignor to The Akron Standard Mold Company, Akron, Ohio, a corporation of Ohio

Application March 11, 1932, Serial No. 598,195

20 Claims. (Cl. 154—9)

This invention relates to collapsible forms or mandrels, and especially those employed in building pneumatic tire casings by the semi-flat band system. When the ultimate tire casing is of relatively-small bead diameter and large section, difficulties are encountered in collapsing the drum to a sufficiently small compass to enable the formed band to be withdrawn therefrom. The principal object of my invention is to provide for an increased amount of collapse of the drum or form without sacrifice of strength or liability to derangement in the operation of the drum.

Of the accompanying drawings, Fig. 1 is a front elevation, partly in section, of a drum embodying my improvements and shown in expanded condition.

Fig. 2 is a front elevation showing the drum collapsed.

Fig. 3 is a longitudinal section on the line 3—3 of Fig. 1, partly in elevation.

Fig. 4 is a detail section on the line 4—4 of Fig. 1, on an enlarged scale.

Fig. 5 is a section of one of the drum segments looking from the position 5—5 of Fig. 3.

The invention is shown applied to a rotary tire-building drum of the general type illustrated in my prior application, Ser. No. 436,716, filed May 18, 1930, but may be used in other connections. These drums are expandable by the action of centrifugal force and collapsible during the rotation thereof by the application of a controlling device such as a brake.

In the drawings, 10 is the rotary shaft of a tire-building machine and 11 designates the collapsible form or drum as a whole. 12 is a spider or drum-segment support fixed on the end of shaft 10. 13, 15 are a pair of drum segments provided with hinge lugs 14 at their heel ends pivoted on pins 15 located at opposite ends of the spider 12 and at fixed distances from the central axis of the shaft. 16, 18 are a complementary pair of drum segments pivoted to swing oppositely to the segments 13 and provided with heel-end hinge lugs 17 straddling the lugs 14 and pivoted to the latter by pins 18 which are spaced angularly in a circumferential direction and radially outward from the pins 15, the combined structure constituting a compound hinge arrangement including centers which are respectively fixed and movable or floating in relation to the axis of shaft 10.

The free or toe ends of the segments 13, when the drum is expanded, overlap those of the segments 16 in a pair of bevelled joints 19. The work-supporting portions of the heel ends of the

segments 13 and 16, under like conditions, meet in a pair of radial joints 20 which are located substantially on the same diameter of the spider 12 as the floating pivots 18 and hence angularly offset in the direction of said pivots from the diameter D—D of said spider passing through the radially-fixed pivots 15 of the segments 13. The four segments collectively constitute the entire periphery or working surface of the drum, and each of them may be made in parts which are 10 axially adjustable on each other to vary the length of the drum for different widths of tire bands, as in my aforesaid application.

21 is a rotary control collar or toggle member concentrically surrounding the shaft 10 immediately in the rear of the spider 12 and adapted to turn with respect to the latter. 22 is a tubular control shaft surrounding the drum shaft 10 and composed of two members held in non-turning relation to each other and telescoping one on 15 the other for the purpose of accommodating drums of different axial lengths, the forward member of said shaft being attached to the collar 21 and its rear end provided with the drum 20 and a manually-operated brake device 23.

The collar 21 is formed with oppositely-extending arms whose outer ends are connected by short toggle links 24 with the underlapping segments 16 near the free ends of the latter. 25 are longer links of angular form connecting points on 25 the collar 21 nearer to the rotary axis thereof with intermediate points on the overlapping segments 13. Spring-projected latch plungers are mounted to slide in guide bushings 26 in the spider 12 parallel with the latter's axis of rotation and provided with conical ends to engage complementary sockets in the collar 21 for assisting in the final expanding movement of the segments as described in my Patent No. 1,866,390, dated July 5, 1932. The symmetrical disposition 40 of the segments and operating connections places the drum substantially in rotational balance when collapsed. The relation of the pivot centers 15 and 18 and the relation of the links 24, 25 and their pivots to the connected parts is such that 45 during collapse the free ends of the underlapping segments 16 first move inwardly in properly timed relation to the overlapping segments 13 to avoid interference.

A desirable feature contributing to an additional reduction in dimensions of the drum in its collapsed condition, along its minor or vertical axis as viewed in Fig. 2, resides in providing arcuate skirt members 27 in radial planes on the two edges of each of the segments 13 and 16, each 55

skirt member being mounted on the inner side of one of the edge flanges 28 on the corresponding segment and having a plurality—three in this instance—of radial and semi-radial guide slots 5 occupied by guide pins 30 in the form of skirt-retaining cap screws fixed in the flange 28, leaf springs 31 fixed to the inner side of the segment being interposed between said segment and the outer edge of the skirt member for yieldingly 10 forcing said member inwardly. The drum flanges 28 act as bead seats and may be of different shapes and radial depths according to the bead posture and the height of drum crown desired. Their inner edges are beveled to meet the skirt plates 27, which may normally act as lateral supports and trimming surfaces for the margins of the fabric plies in the tire band. When the outlying segments 13 are brought against the underlying segments 16 in the collapsed condition, their skirt members 27 yield against the springs 31 to permit the maximum degree of reduction in drum diameter along the minor axis. There may be a similar yielding of skirt members on the underlying segments 16 15 upon encountering some part of the central structure such as the tubular shaft 22 where a particularly high-crowned drum of small diameter is employed. The yielding of the skirt members 27 on the outlying segments 13 is represented in Fig. 2 as though their movement were in parallelism with themselves although the pressure is at the free end of the segment, but the movement may also be more or less or wholly pivotal on the pin 30 nearest the heel of the segment as a fulcrum, the slots 29 being suitably shaped or sized to permit such pivotal movement.

Rubber bumpers 22' mounted on fixed seats on the spider 12 may be provided as cushioning stops for the arms of the control collar 21 at the limit of 40 the latter's drum-collapsing movement.

In the operation of this invention, drum rotation is counter-clockwise as viewed in Figs. 1 and 2 although the parts might be rearranged for the opposite direction. When it is desired to collapse 45 the drum to remove the tire band which has been built thereon, the driving power is cut off from shaft 10, and while the drum is still in rotation the brake 23 is applied to retard the toggle collar 21 with relation to the drum segments. This causes 50 the free ends of the underlapping segments 16 to be swung inwardly and those of the overlapping segments 13 first to be moved slightly outward, followed immediately by an inward swinging movement of the segments 13 so that the two segments 13 and 16 on each side will lie one over the other in the collapsed condition of the drum, as seen in Fig. 2.

The heel corners of the segments 13, being angularly offset from the diameter D—D as previously described, are carried on a rather steep angle inwardly from the expanded circle 11a of the drum, and the segments 16, having their heels hinged to those of the segments 13, will undergo a corresponding inward movement of their heel corners, so that in the final collapsed condition of the drum this major diameter, lengthwise of the spider 12, will be reduced very considerably from the expanded diameter of the drum. This aids materially in the removal of a tire band having beads of relatively small diameter. Furthermore, when the skirt members 27 on the segments encounter an underlying structure, said skirt members may yield against the pressure of the springs 31 and thus accomplish a further reduction of dimension of the collapsed drum along its

minor diameter. When the drum 16 is to be used for building another band, it may be automatically expanded by the action of centrifugal force when the shaft 10 is set in rotation.

It will be understood that the described form of embodiment may be considerably varied without departing from the scope of the invention as defined in the claims.

I claim:

1. A collapsible drum structure comprising a 10 central rotary support, a drum whose periphery is composed entirely of segments movable inwardly to a collapsed position substantially in rotational balance and including a segment having a heel portion pivoted at a fixed center on the support, and another segment having an adjacent heel portion mounted on a pivot movable inwardly toward the drum center during collapse of the drum, and means rotatable with relation to said support, concentrically with the latter's axis of 15 rotation, for collapsing the drum and for so moving said movable pivot during collapse.

2. A collapsible drum structure comprising a rotary spider, and two oppositely-swinging pairs of segments supported by said spider at opposite 25 sides of the latter's axis of rotation, a member of each pair being connected with a member of the other pair and with the spider by a compound hinge device to turn about different centers of which one is fixed on the spider and the other 30 movable around the fixed center.

3. A collapsible drum structure comprising a rotary segment support, a segment having a heel lug pivoted on a center radially fixed on said support, and another segment having a heel lug pivoted on the lug of the first segment on a center spaced from the latter's pivot.

4. A collapsible drum structure comprising a rotary shaft having a spider fixed thereon, a pair of segments pivoted at opposite fixed centers 40 thereon, a second pair of segments coacting with the first-said pair to form the drum surface and underlying the members of said first pair when the drum is collapsed, the members of the second pair having floating pivots on the members of the 45 first pair, and a controlling member surrounding said shaft and connected to the respective segments for collapsing the drum during rotation.

5. A collapsible drum structure comprising a rotary segment support, a drum segment pivoted 50 thereon, and an adjacent second segment having a floating pivot on said first segment and substantially meeting the latter, when the drum is expanded, in a heel joint offset in the direction of the floating pivot, from a diameter of said support 55 passing through the pivotal axis of the first segment.

6. A drum formed of oppositely swinging segments having heel portions connected by a floating pivot whereby they are hinged one upon 60 another for collapsing the drum, by swinging movement of the segments, to a major diameter smaller than the expanded diameter of the drum, and additional means carried by said segments for reducing the minor diameter of the drum in its 65 collapsed condition.

7. A collapsible chuck comprising a supporting member, an arm secured thereto intermediate its ends, a pair of arcuate segments, each segment pivotally connected to an end of the arm, 70 an arcuate segment pivotally connected to each of the first mentioned segments, and means for moving the free ends of all the segments.

8. A collapsible chuck comprising a supporting member, an arm secured thereto intermediate its 75

- 5 ends, a pair of arcuate segments, each segment pivotally connected to an end of the arm, an arcuate segment pivotally connected to each of the first mentioned segments adjacent the secured ends of the latter, a shorter arm rotatably mounted intermediate its ends on the supporting member, and means pivotally connecting the free ends of the shorter arm to points adjacent the free ends of one of the arcuate segments.
- 10 9. A collapsible chuck comprising a supporting member, an arm secured thereto intermediate its ends, a pair of arcuate segments, each segment pivotally connected to an end of the arm, an arcuate segment pivotally connected to each of the first mentioned segments, the segments when placed together in end to end relation being adapted to form a substantially circular drum, and means for moving the free ends of all of the segments out of and into end to end relation.
- 15 10. A collapsible chuck comprising a supporting member, an arm secured thereto intermediate its ends, pairs of arcuate segments pivotally secured together, one segment of each pair being pivotally connected to an end of the arm, the segments being so disposed as to form a substantially circular drum, a shorter arm rotatably mounted intermediate its ends on the supporting member, and means pivotally connecting each end of the shorter arm to a point adjacent the free ends of one of the segments.
- 20 11. The combination in an annular collapsible tire building form of opposite pairs of adjacent sections, the sections of each pair being pivotally connected by a floating pivot, supporting means at the center of the form for mounting the same including a power driven shaft, and means associated with said supporting means and connected with the sections to swing and bodily move all of said sections as a whole inwardly from their normal positions in the form circle to collapsed positions in which the sections of each pair embrace a section of each other pair, said pivots moving inwardly toward the center of the form.
- 25 12. The combination in an annular collapsible tire building form of opposite pairs of adjacent sections, the sections of each pair being pivotally connected by a floating pivot, supporting means at the center of the form for mounting the same including relatively rotatable members, and means associated with said supporting means and connected with the sections to swing and bodily move all of said sections as a whole inwardly from their normal positions in the form circle to collapsed positions in which the sections of each

pair embrace a section of each other pair, said pivots moving inwardly toward the center of the form.

13. The combination in an annular collapsible tire building form of opposite pairs of adjacent sections, the sections of each pair being pivotally connected by a floating pivot, supporting means at the center of the form for mounting the same including a power driven shaft, and means associated with said supporting means and connected with the sections to swing and bodily move all of said sections as a whole inwardly from their normal positions in the form circle, said pivots moving inwardly toward the center of the form.

14. The combination in an annular collapsible tire building form of opposite pairs of adjacent sections, the sections of each pair being pivotally connected by a floating pivot, supporting means at the center of the form for mounting the same including relatively rotatable members, and means associated with said supporting means and connected with said members and operable by relative rotation thereof to swing and bodily move all of said sections as a whole inwardly from their normal positions in the form circle, said pivots moving inwardly toward the center of the form.

15. A drum according to claim 6 in which the additional means is a marginal flange or skirt structure movable on the segment structure. 30

16. A drum having a hinged segment, means hingedly supporting the same, and a marginal flange or skirt member movable on said segment to reduce the radial depth of the segment.

17. A drum composed of hinged segments collapsible to an overlapping relation, a support by which they are hingedly carried, and skirt members guided for relative outward movement on certain of said segments. 35

18. A drum composed of hinged segments collapsible to an overlapping relation, a carrier therefor, and skirt members on the outlying segments adapted to contact with the underlapping ones and guided for relative outward movement on said outlying segments. 40 45

19. In a rotary form, a movable segment having an inner peripheral flange, a skirt member mounted for movement transversely of the outer periphery of said segment on the interior side of said flange and having pin-and-slot guiding connections with the flange, and spring means for inwardly moving said member.

20. A drum having a segment having a hingedly supported heel portion, a support therefor, and an edge skirt pivoted on said segment in the vicinity of the latter's heel portion. 50 55

HENRY C. BOSTWICK.
